US0D1096881S

(12) **United States Design Patent** (10) Patent No.: **US D1,096,881 S**
(45) Date of Patent: ** Oct. 7, 2025

(54) **SCIENCE, TECHNOLOGY, ENGINEERING, AND MATH CONSTRUCTION COUPLER**

(71) Applicant: **SPHERO, INC.**, Boulder, CO (US)

(72) Inventors: **Paul David Copioli**, Rockwall, TX (US); **Arthur Philip Dutra, IV**, Elk Grove, CA (US); **Charles Michael Wensel**, Frisco, TX (US)

(73) Assignee: **SPHERO, INC.**, Greenville, TX (US)

(***) Term: **15 Years**

(21) Appl. No.: **29/870,147**

(22) Filed: **Jan. 17, 2023**

(51) LOC (15) Cl. 21-01

(52) U.S. Cl.

USPC **D21/484**; D15/199

(57) **CLAIM**

The ornamental design for a science, technology, engineering, and math construction coupler, as shown and described.

DESCRIPTION

FIG. 1 is a top, front perspective view of a science, technology, engineering, and math construction coupler illustrating our new design.

FIG. 2 is a bottom, rear perspective view thereof.

FIG. 3 is a front view thereof.

FIG. 4 is a rear view thereof.

FIG. 5 is a top view thereof.

FIG. 6 is a bottom view thereof.

FIG. 7 is a left side view thereof; and,

FIG. 8 is a right side view thereof.

Portions of the science, technology, engineering, and math construction coupler shown with broken lines form no part of the claimed design.

1 Claim, 8 Drawing Sheets
